UNITED STATES PATENT OFFICE.

WARREN W. GORE, OF MADISON, WISCONSIN, ASSIGNOR TO FULLER & JOHNSON M'F'G CO., OF MADISON, WISCONSIN, A CORPORATION OF WISCONSIN.

FUEL-FEED DEVICE FOR ENGINES.

1,293,756.

Specification of Letters Patent.

Patented Feb. 11, 1919.

Application filed February 5, 1918. Serial No. 215,453.

To all whom it may concern:

Be it known that I, WARREN W. GORE, a citizen of the United States, residing at Madison, in the county of Dane and State of Wisconsin, have invented certain new and useful Improvements in Fuel-Feed Devices or Engines, of which the following is a specification.

This invention relates to devices for feeding liquid fuel to internal combustion engines, and has reference more particularly to a fuel feeding device for use on engines using kerosene, or other comparatively heavy hydrocarbon fuel. Owing to the difficulty of starting on kerosene, it is customary to start kerosene engines with gasoline, and, after they are primed and sufficiently heated to vaporize the kerosene, to then cut out the gasoline and switch on the kerosene.

The main object of the present invention is to provide a simple and easily manipulated device to facilitate these operations which shall dispense with the necessity of separate gasoline and kerosene receptacles. Other objects are, to provide a fuel feed device which may dispense with the usual float-amber attachment to the charge-forming device or carburetor while maintaining a constant level of the liquid fuel in the latter, to provide a device which may employ either a vacuum tank or a positive feed pump for drawing the kerosene from the main supply tank, to provide a fuel feed device capable of delivering first pure gasoline, then automatically changing to a mixture of gasoline and kerosene, and finally delivering pure kerosene to the engine, and to provide a fuel feed device of such a character that, by the manipulation of a single valve, the entirety of kerosene in a reservoir intermediate the main supply tank and the carburetor can be drained back into the main supply tank, the reservoir re-filled with gasoline for starting the engine. Still another object is to provide in a fuel feed device means by which the normal fuel feed passages to the carburetor can be drained into the main supply tank at the same time that the reservoir is drained, so as to completely empty the passages of the heavier fuel preliminary to filling with the lighter fuel.

Other objects and attendant advantages of the invention will be readily understood and appreciated by those skilled in the art.

from the following detailed description, taken in connection with the accompanying drawings wherein I have illustrated practical and workable embodiments of the principle of the invention, and in which—

Figure 1 is a view of the complete device partly in elevation and partly in vertical section, including an engine cylinder and piston;

Fig. 2 is a view similar to the left half, of Fig. 1, showing the use of a positive feed fuel pump in lieu of the vacuum tank of Fig. 1; and

Fig. 3 is a detail view, illustrating an alternative form of drain valve which may be employed in lieu of the drain valve shown in Figs. 1 and 2.

Referring to Fig. 1 of the drawings, 5 designates the main fuel supply tank designed to contain kerosene or other relatively heavy hydrocarbon fuel. 6 is a vacuum tank generally similar to those at present employed for drawing the fuel from the main supply tank to a point sufficiently elevated above the carburetor to insure a steady gravity flow to the latter, this vacuum tank being equipped with the usual float-controlled valve 7 in its bottom for maintaining a substantially constant level of fuel in the vacuum tank, as usual. The top portion of the vacuum tank is connected by a pipe 8 with the main fuel tank 5, and by a pipe 9 with the intake manifold 10 of the engine, the working cylinder of which is shown at 11.

Secured to and directly below the bottom of the vacuum tank 6 is a reservoir or receptacle 12 into which the fuel is admitted from the vacuum tank by the valve 7. To the bottom of the reservoir 12 is secured a valve casing 13 formed with a horizontal duct 14, a vertical duct 15 connecting the duct 14 with the reservoir 12 through a registering port 16 in the bottom of the latter, and a vertical overflow and drain duct 17 intersecting the horizontal duct 14. In the duct 14, between the ducts 15 and 17, is formed a valve seat 18 that is normally closed by a compression valve 19, the stem 20 of which has threaded engagement with a packed tubular extension 13' of the valve casing 13, and is provided at its outer end with a handle 21 for manual turning. A pipe 22 passes through the bottom of reservoir 12 and enters the upper end of the vertical duct 17 of

the valve casing, and another pipe 23 connects the lower end of duct 17 with the main fuel tank 5. The pipes 22 and 23 and the vertical duct 17 of the valve casing together 5 constitute a constant-level overflow connection between the reservoir 12 and the main fuel tank 5, while port 16, ducts 15 and 14, the lower portion of duct 17, and the pipe 23 together constitute a valve-controlled drain 10 for the reservoir to the main fuel tank in a manner more particularly hereafter explained. The stem of valve 19, where it intersects the vertical duct 17, is reduced, as shown at 20', so as not to obstruct the overflow 15 through pipe 22, duct 17, and pipe 23. The right-hand end of valve-casing 13 is connected by a pipe 24 that communicates with duct 14 with a charge-forming device or carburetor which, in the simple form here 20 shown, may consist of a tube 25 connected to the engine manifold 10 and containing a mixer and vaporizer consisting of a nozzle 26 delivering the fuel at the throat of a Venturi-tube 27; the lower end of nozzle 26 25 being mounted in an internal bracket casting of the pipe 25 that is cored to provide an L-shaped duct 28 connecting pipe 24 and nozzle 26; this duct being preferably controlled by a manually operated throttle 30 valve 29, which is always open to a greater or less extent.

At 30 is shown a gasolene filling pipe that communicates with the upper portion of the reservoir 12 and is formed with a funnel-shaped upper end or mouth 30', in which is preferably placed a screen 31. 32 is an air vent opening at the upper end of the reservoir 12 for maintaining atmospheric pressure on the liquid therein where the filling 35 tube is sealed, as will preferably be done, to exclude dirt.

In operation, assuming that the engine is cold and that the reservoir and carburetor are filled with kerosene from the last running to the height of the overflow tube 22, the valve 19 is backed off, and all the kerosene in reservoir 12 is permitted to drain back into the tank 5. This also drains the carburetor and the passages leading thereto.

50 The valve 19 is then closed, and gasolene is poured into the reservoir through filling tube 30 preferably to the height of the overflow tube 22, the gasolene of course standing at the same level in the carburetor nozzle 26.

55 The engine is then started in operation on pure gasolene. Shortly thereafter, however, the vacuum tank 6 begins to supply kerosene to the gasolene in the reservoir 12, so that for a while the engine operates on a mixture 60 that gradually becomes leaner in gasolene and richer in kerosene, until all of the gasolene has been consumed. By that time, however, the engine has become sufficiently heated to vaporize the pure kerosene and run on 65 that alone.

The modification shown in Fig. 2 simply dispenses with the vacuum tank 6 of Fig. 1 as a means of supplying kerosene to the reservoir 12, and substitutes therefor a positive feed fuel pump 33 that draws kerosene 70 from the tank 5 and forces it through a delivery pipe 34 into the fuel reservoir 12.

Fig. 3 illustrates another form of drain valve that may be substituted for the compression drain valve previously described 75 and shown in Figs. 1 and 2; this modification consisting of an ordinary tapered and ground cock 35 mounted in the valve casing and intersecting the duct 14 of the latter, said cock having a transverse port 36 that 80 in the normal running of the engine occupies the position shown, but, for draining purposes, preliminary to starting, may be turned so as to establish the drain passage from the reservoir 12 to the main fuel 85 tank 5.

I claim:—

1. In a fuel feed device for engines, the combination of a main fuel tank, a fuel reservoir located at a higher level than said tank, means for causing fuel to flow from said main tank to said reservoir, an overflow pipe in said reservoir, a reservoir drain pipe connected into said main fuel tank, a charge-forming device, and a cored valve-casing having a continuously open duct connecting said overflow and drain pipes, a continuously open duct connecting said reservoir and charge-forming device, and a valve-controlled duct connecting said reservoir and drain pipe. 90

2. In a fuel feed device for engines, the combination of a main fuel tank, a fuel reservoir located at a higher level than said tank, means for causing fuel to flow from said main tank to said reservoir, an overflow pipe in said reservoir leading through the bottom of the latter, a reservoir drain pipe connected into said main fuel tank, a charge-forming device, a cored valve casing having 110 a continuously open duct connecting said overflow and drain pipes, a continuously open duct connecting said reservoir and charge-forming device, and a duct connecting said reservoir and drain pipe, a manually operable valve for opening and closing said last-named duct, and a filling tube connected into the upper portion of said reservoir. 115

3. In a fuel feed device for engines, the combination of a main fuel tank, a fuel reservoir located at a higher level than said tank, means for causing fuel to flow from said main tank to said reservoir, a charge-forming device, a continuously open fuel 120 supply passage leading from said reservoir to said charge-forming device, and a valve-controlled drain passage leading from the bottom of said reservoir to said fuel tank, said drain passage and said fuel supply 125 130

passage having a common communication with the bottom of said reservoir.

4. In a fuel feed device for engines, the combination of a main fuel tank, a fuel reservoir located at a higher level than said tank, means for causing fuel to flow from said main tank to said reservoir, a drain pipe connected into said main fuel tank,

a charge-forming device, and a cored valve casing having a continuously open duct connecting said reservoir and charge-forming device, and a valve-controlled duct connecting said continuously open duct and said drain pipe. 10

WARREN W. GORE.
